[57] CLAIM

The ornamental design for a combined container with minerals and letter opener, as shown and described.

DESCRIPTION

FIG. 1 is a perspective view of a combined container with minerals and letter opener showing my new design;

FIG. 2 is a front elevational view thereof;

FIG. 3 is a rear elevational view thereof;

FIG. 4 is a top plan view thereof;

FIG. 5 is a left side elevation view thereof;

FIG. 6 is a bottom plan view thereof;

FIG. 7 is a right side elevation view thereof;

FIG. 8 is a perspective view thereof of a second embodiment of that shown in FIG. 1;

FIG. 9 is a front elevational view thereof;

FIG. 10 is a rear elevational view thereof;

FIG. 11 is a top plan view thereof;

FIG. 12 is a left side elevation view thereof;

FIG. 13 is a bottom plan view thereof; and

FIG. 14 is a right side elevation view thereof.
